C. A. Mason, Atty.

UNITED STATES PATENT OFFICE.

WILLIAM H. GREEN, OF NEW YORK, N. Y., ASSIGNOR TO THE REMILLER CO., OF NEW YORK, N. Y., A CORPORATION OF NEW YORK.

DESIGN FOR A FACE-POWDER BOX.

Application filed December 7, 1922. Serial No. 4,518. Term of patent 14 years.

To all whom it may concern:

Be it known that I, WILLIAM H. GREEN, citizen of the United States, and resident of the city of New York, county of Queens, State of New York, have invented a new, original, and ornamental Design for a Box for Face Powder, of which the following is a specification, reference being had to the accompanying drawings, forming a part thereof.

Fig. 1 is a perspective view of a box illustrating my new design, and
Fig. 2 is a plan view.

I claim:

The ornamental design for a face powder box, substantially as shown.

WILLIAM H. GREEN.
